[57] CLAIM

The ornamental design for telephone set, as shown.

DESCRIPTION

FIG. 1 is a plan view of the telephone set according to my design; and,

FIG. 2 is a left-side elevational view of the telephone set according to my design, the right-side elevational view being a mirror image of the left-side elevational view.

The portions of the claimed article not shown in the drawings are not considered to be part of my claimed design.

1 Claim, 2 Drawing Sheets

FIG. 1

FIG. 2
